CLAIM

The ornamental design for a closet hanger rod connector, as shown and described.

DESCRIPTION

FIG. 1 is a top view of my closet hanger rod connector showing my new design;

FIG. 2 is a front view thereof;

FIG. 3 is a right side view thereof, the left side being a mirror image;

FIG. 4 is a rear view thereof;

FIG. 5 is a bottom plan view thereof;

FIG. 6 is a perspective view thereof, the hanger rods being shown in broken lines for illustrative purposes only.
